UNITED STATES PATENT OFFICE

WILLIAM FERGUSON, OF FLINT, MICHIGAN

SHEET-METAL BUMPING-OUT TOOL

Application filed May 4, 1928, Serial No. 275,216. Renewed September 27, 1929.

This invention relates to bumping-out tools to be used in removing indentations from sheet metal, and more particularly for use in bumping out indentations in automobile bodies due to collisions and accidents, and the invention has for its object to provide a tool of such class, in a manner as hereinafter set forth for reaching a certain part of an automobile body without the necessity of tearing down the inner frame or supporting structure to get at the indentation in the metal for the purpose of bumping it out.

In removing indentations from the sheet metal body and fenders of an automobile it is now the ordinary practice to hold a metal block or dolly against the inner face of the indented structure while blows are delivered by a hammer to the outer surface of this structure. It frequently happens however that access to the inner surface of the portion of the automobile that is indented is obstructed by adjacent braces, beams or backing frame so that the dolly or bumping-out block can not be placed against the inner surface of the indented structure until this obstructing inner structure has been removed.

The present invention is therefore directed to a bumping-out tool or tools having a relatively thin blade-like anvil adapted to be inserted between an indented portion of an automobile and a closely adjacent brace, beam or supporting structure so that the indentation may be bumped out without necessitating the removal and subsequent replacement of the adjacent inner supporting structure.

In bumping out metal the bumping-out tool held against the work should be sufficiently heavy to cause its inertia of rest to resist the bumping-out blows of the hammer, but when a blade-like anvil such as contemplated by the present invention is employed to back-up the metal surface being bumped-out, the weight or inertia of rest of this anvil may not be sufficient to resist the blows of the hammer.

To overcome this difficulty the present in-

vention contemplates a construction in which the blade-like anvil is provided with a relatively heavy handle which is positioned in spaced relation to the anvil where it will be out of the way of the supporting structure disposed adjacent the surface to be bumped-out, and the heavy handle and blade are connected by a coupling portion that is sufficiently rigid to impart the blows against the anvil to the heavy handle.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a side elevation, broken away, of a tool in accordance with this invention for bumping out metal.

Figure 2 is a front elevation of the tool of Fig. 1.

Figures 3, 4 and 5 are respectively sections on lines 3—3, 4—4 and 5—5 of Figure 1.

Figure 6 is a side elevation of a modified form of tool in accordance with this invention for bumping out metal.

Figure 7 is a rear elevation thereof.

Figures 8 and 9 are sections respectively on lines 8—8 and 9—9 of Figure 6.

The tool illustrated in Figure 1 is termed a cowl post spoon and comprises a handle 10 which may be of polygonal cross section to facilitate the firm gripping of the handle in the hand, and the handle may have any desired length and at one end thereof terminates in a right angularly directed, curved coupling portion 11 having a flared part 12 which merges into an anvil 13 disposed substantially

at right angles with respect to the coupling portion 11 and opposing the handle 10, as well as arranged in spaced relation with respect thereto.

5 The anvil 13 is preferably given the blade-like construction shown so that it may be inserted between the inner face of the sheet metal structure to be bumped out and an adjacent support or backing frame, and the 10 outer end of the anvil is preferably made quite thin to facilitate its insertion between contacting or closely adjacent surfaces. The thickness of the anvil may increase from its outer to its inner end as shown to impart to 15 the anvil sufficient strength and stiffness to withstand the blows of the bumping-out hammer. The coupling portion 11 between the handle 10 and anvil 13 is sufficiently rigid to cause the blows delivered to the anvil to 20 be directly imparted to the relatively heavy handle so that the weight of the entire tool will resist displacement of the anvil under the hammer blows, and as above stated the handle 10 is spaced from the anvil 13 a sufficient 25 distance to clear a brace, beam or other structure which may occupy the space between the blade and handle during the bumping-out operation. The construction of the entire tool is such that the handle 10 may 30 readily be grasped in one hand to hold the blade 13 against the inner surface of the structure to be bumped out while blows are delivered by a hammer to the outer surface of the indented structure.

35 The anvil 13 illustrated gradually increases in width from its inner toward its outer end whereby its outer end will be of greater width than its inner end. The outer corners of the anvil 13 are rounded as indicated at 14. The anvil 13 is disposed upon a slight inward curve whereby the free end thereof will project toward the handle 10. The outer face of the anvil 13 is of arcuate contour longitudinally and transversely to 45 present a curved surface to the metal to be bumped out.

The tool as shown in Figure 6 is what is termed a single face spoon and comprises a polygonal handle 15 terminating at one end 50 in a substantially, right angularly directed, curved tapered coupling portion 16 which merges into a lengthwise curved anvil 17 opposing and spaced from the handle 15. The outer face of the anvil 17 is of arcuate contour. The anvil 17 is upon a slight curve and is of less length than the handle 15 but of 55 materially greater width than that of the latter. The anvil 17 is disposed substantially at right angles to the coupling portion 16. The free end of anvil 17 is directed toward 60 the handle 15. The handle 15 is not curved and extends in the same plane throughout. The coupling portion 16 is of the desired length so as to maintain the anvil 17 an appropriate distance from the handle 15. The

inner face of the anvil 17 is flat and uninterrupted throughout and its outer face of arcuate curvature longitudinally and transversely. The anvil 17 gradually decreases in thickness from its inner towards its outer end and the major portion thereof is of uniform width. The free ends of the anvil and handle are beveled as at 18, 19 respectively.

70 In each of the bumping-out tools illustrated the anvil is given a flattened construction to facilitate its insertion between an indented surface and adjacent brace or other structure, and the handle is made relatively heavy and is rigidly connected to the anvil so that blows imparted to the anvil will be 75 delivered directly to the handle. In the construction shown in Fig. 1 the handle is made long as compared with the tool of Fig. 6 to increase the reach of the tool and the blade is comparatively thin, whereas in the tool of 80 Fig. 6 the blade is relatively thick toward its rear end and blends into the curved coupling portion 16 to increase the rigidity of the entire tool. Each of the tools illustrated is so constructed that when the handle is grasped 85 in the hand the anvil will lie opposite the hand in spaced relation thereto to facilitate holding the anvil firmly against the work being bumped out.

90 What I claim is:

1. A bumping tool comprising a handle, a coupling portion extending at an angle from one end thereof, and an anvil integral with said portion and disposed substantially in parallel spaced relation with respect to the handle and having its inner face uninterrupted throughout.

95 2. A bumping tool comprising a handle, a coupling portion extending substantially at right angles with respect thereto and integral with one end thereof, and an anvil integral with said portion, disposed substantially at right angles with respect thereto and further positioned in substantial parallel spaced relation with respect to a part of the handle, said anvil being of greater width than the handle.

100 3. A bumping tool comprising a handle, a coupling portion extending at an angle from one end thereof, and an anvil integral with said portion and disposed in substantially parallel spaced relation with respect to the handle, said anvil having its outer face of arcuate contour and its inner face flat and uninterrupted throughout.

105 4. A bumping tool comprising a handle, a coupling portion extending substantially at right angles with respect thereto and integral with one end thereof, and an anvil integral with said portion, disposed substantially at right angles with respect thereto and further positioned in substantially parallel spaced relation with respect to the handle, said anvil being of greater width than that of the handle and having its outer face of arcuate contour.

5. A bumping tool comprising a handle, a coupling portion extending at an angle from one end thereof, and an anvil integral with said portion and disposed in substantially parallel spaced relation with respect to the handle, said anvil of greater width than said handle and gradually decreasing in thickness from its inner toward its outer end and having its outer face of arcuate contour. 5
10. A bumping tool comprising a handle, a coupling portion extending at an angle from one end thereof, an anvil integral with said portion and disposed in substantially parallel spaced relation with respect to the handle, and said anvil of less thickness and greater width than the handle and having its inner face uninterrupted throughout. 10
15. A bumping tool comprising a handle, a coupling portion extending substantially at right angles with respect thereto and integral with one end thereof, an anvil integral with said portion, disposed substantially at right angles with respect thereto and further positioned in substantially parallel spaced relation with respect to the handle, and said anvil of less thickness and greater width than the handle and having its outer face of arcuate contour and its inner face uninterrupted throughout. 25
20. A bumping tool comprising a handle, a coupling portion extending at an angle from one end thereof, an anvil integral with said portion and disposed in substantially parallel spaced relation with respect to the handle, and said anvil gradually decreasing in thickness from its inner to its outer end and having its outer face of arcuate contour. 30
25. A bumping tool comprising a handle, a coupling portion extending substantially at right angles with respect thereto and integral with one end thereof, an anvil integral with said portion, disposed substantially at right angles with respect thereto and further positioned in substantial parallel spaced relation with respect to the handle, and said anvil gradually decreasing in thickness from its inner to its outer end and having its outer face of arcuate contour. 35
30. A bumping tool comprising a handle, a coupling portion extending at an angle from one end thereof, an anvil integral with said portion and disposed in substantially parallel spaced relation with respect to the handle, and said anvil having its outer face of arcuate contour transversely and longitudinally and having its inner face flat and uninterrupted throughout. 40
35. A bumping tool comprising a handle, a coupling portion extending substantially at right angles with respect thereto and integral with one end thereof, an anvil integral with said portion, disposed substantially at right angles with respect thereto and further positioned in substantially parallel spaced relation with respect to the handle, said anvil having its outer face of arcuate contour. 45
40. A bumping tool comprising a handle, a coupling portion extending at an angle from one end thereof, an anvil integral with said portion and disposed in substantially parallel spaced relation with respect to the handle, and said anvil having its outer face of arcuate contour transversely and longitudinally and its inner face uninterrupted throughout. 50
45. A bumping tool comprising a handle, a coupling portion extending substantially at right angles with respect thereto and integral with one end thereof, and an anvil integral with said portion, disposed substantially at right angles with respect thereto and further positioned in substantially parallel spaced relation with respect to the handle, said anvil having its outer face of arcuate contour. 55
50. A bumping tool comprising a handle, a coupling portion extending at an angle from one end thereof, an anvil integral with said portion and disposed in substantially parallel spaced relation with respect to the handle, and said anvil being slightly curved and having its free end directed toward said handle and having that face thereof opposing the handle uninterrupted throughout. 60
55. A bumping-out tool for removing indentations in the metal structure of a vehicle, comprising a blade-like anvil having a bumping surface extending longitudinally of the anvil, and a handle connected to the anvil at one end thereof and disposed in spaced approximately parallel relation to the anvil. 65
60. A bumping-out tool for removing indentations in the metal structure of a vehicle, comprising a blade-like anvil having a bumping surface extending longitudinally of the anvil, a coupling portion extending laterally from one end of the anvil, and a handle opposite the anvil in spaced relation thereto and rigidly connected to the anvil by the coupling portion to extend in the same general direction as the anvil. 70
65. A bumping-out tool for removing indentations in the metal structure of a vehicle, comprising an elongated anvil having a bumping surface extending longitudinally of the anvil, and a handle rigidly connected to the anvil at one end thereof and disposed opposite the anvil in spaced relation thereto to extend in the general direction of the anvil. 75
70. A bumping-out tool for removing indentations in the metal structure of a vehicle, comprising an elongated anvil that diminishes in thickness from one end toward the other and having a bumping surface extending longitudinally of the anvil, and a handle rigidly connected to the anvil at one end thereof and disposed in spaced approximately parallel relation thereto. 80
75. A bumping-out tool for removing indentations in the metal structure of a vehicle, comprising a blade-like anvil having a thin terminal end for facilitating its insertion between the indented portion of the vehicle and adjacent structure and having a bumping surface extending lengthwise of the anvil, and a handle connected to the opposite end of the blade-like anvil and disposed in spaced approximately parallel relation to the anvil. 85
80. A bumping-out tool for removing indentations in the metal structure of a vehicle, comprising an elongated anvil having a bumping surface extending lengthwise of the anvil, and a relatively heavy handle rigidly connected to one end of the anvil to lie in approximately parallel relation to the anvil and adapted to resist the blows of the bumping-out operation by its inertia of rest. 90
85. A bumping-out tool for removing indentations in the metal structure of a vehicle, comprising an elongated anvil having a bumping surface extending lengthwise of the anvil, and a handle rigidly connected to one end of the anvil to lie in approximately parallel relation to the anvil and adapted to resist the blows of the bumping-out operation by its inertia of rest. 95
90. A bumping-out tool for removing indentations in the metal structure of a vehicle, comprising an elongated anvil having a bumping surface extending lengthwise of the anvil, and a handle rigidly connected to one end of the anvil to lie in approximately parallel relation to the anvil and adapted to resist the blows of the bumping-out operation by its inertia of rest. 100
95. A bumping-out tool for removing indentations in the metal structure of a vehicle, comprising an elongated anvil having a bumping surface extending lengthwise of the anvil, and a handle rigidly connected to one end of the anvil to lie in approximately parallel relation to the anvil. 105
100. A bumping-out tool for removing indentations in the metal structure of a vehicle, comprising an elongated anvil having a bumping surface extending lengthwise of the anvil, and a handle rigidly connected to one end of the anvil to lie in approximately parallel relation to the anvil. 110
105. A bumping-out tool for removing indentations in the metal structure of a vehicle, comprising an elongated anvil having a bumping surface extending lengthwise of the anvil, and a handle rigidly connected to one end of the anvil to lie in approximately parallel relation to the anvil. 115
110. A bumping-out tool for removing indentations in the metal structure of a vehicle, comprising an elongated anvil having a bumping surface extending lengthwise of the anvil, and a handle rigidly connected to one end of the anvil to lie in approximately parallel relation to the anvil. 120
115. A bumping-out tool for removing indentations in the metal structure of a vehicle, comprising an elongated anvil having a bumping surface extending lengthwise of the anvil, and a handle rigidly connected to one end of the anvil to lie in approximately parallel relation to the anvil. 125
120. A bumping-out tool for removing indentations in the metal structure of a vehicle, comprising an elongated anvil having a bumping surface extending lengthwise of the anvil, and a handle rigidly connected to one end of the anvil to lie in approximately parallel relation to the anvil. 130

19. A bumping-out tool for removing indentations in the metal structure of a vehicle, comprising an elongated anvil having a bumping surface extending lengthwise of the anvil, and a handle rigidly connected to one end of the anvil to lie in approximately parallel relation to the anvil but at a substantial distance therefrom to provide a large clearance space between the handle and anvil.
- 10 In testimony whereof, I affix my signature hereto.

WILLIAM FERGUSON.
